UNITED STATES PATENT OFFICE.

JOHN JUNKUNC, OF CHICAGO, ILLINOIS.

KEY LOCK.

1,411,280.

Specification of Letters Patent. Patented Apr. 4, 1922.

Application filed January 7, 1921. Serial No. 435,595.

To all whom it may concern:

Be it known that I, JOHN JUNKUNC, a citizen of the United States, and a resident of the city of Chicago, in the county of Cook and State of Illinois, have invented a certain new and useful Key Lock; and I do hereby declare that the following is a full, clear, and exact description of the same, reference being had to the accompanying drawings, and to the numerals of reference marked thereon, which form a part of this specification.

This invention relates to a lock of the type that is operated by having a key thrust into it and does not require the rotation of the key.

It is an object of this invention to provide such a lock that can be made of parts that are inexpensively manufactured.

It is a further object of this invention to produce a system of locks wherein the individual locks may be varied so as to require different keys without requiring any special or complicated manufacturing processes to produce the necessary accuracy.

It is a further object of this invention to present to the operation of the key a set of locking slides which will be all brought into unlocking position when the key is thrust into place.

It is a further object of this invention to provide one spring which shall hold a plurality of locking slides in their respective locking position.

Other and further important objects of this invention will be apparent from the disclosures in the specification and the accompanying drawings.

The invention (in a preferred form) is shown in the drawings and hereinafter more fully described.

On the drawings:

Figure 1 is a top plan view of the lock.

Figure 2 is a similar view with the cover of the lock casing removed.

Figure 3 is a top plan view of the lock and key with the shackle of the lock in lock position.

Figure 4 is a section just about the bottom of the lock housing, the lock having been reversed to show this section in plan.

Figure 5 is a section on the line 5—5 of Figure 2.

Figure 6 is a section on the line 6—6 of Figure 5.

Figure 7 is a section on the line 7—7 of Figure 5 looking in the direction indicated by the arrows, the shackle being omitted.

Figure 8 is a view similar to Figure 7 showing the key inserted.

Figure 9 is a detail view of one of the sliding locking members, and

Figure 10 is a similar view of another of these members.

As shown on the drawings:

The lock comprises a shackle 1 having legs 2 and 3 which enter into the housing 4. This housing consists of a box 5 and a cover 6 which fits into a shoulder 7. The cover is secured to the box by spinning or otherwise 70 forcing the edge of the wall of the box over it as indicated in Figures 5 and 6.

At the bottom of the box is a piece 8 which is formed with a slot 9 to receive a spring 10. The piece 8 is cut away as indicated at 11 to 75 afford room for the movement of the spring 10. The end of this spring bears against an end 12 upon the leg 3 of the shackle. The purpose of the spring is to force the shackle outwards to the position indicated in 80 Figure 3 when the key has moved the sliding locking members to unlock position.

The central part of this piece 8 is higher than the rest of the piece as indicated at 13 in Figure 5 and as indicated by the sectioned part of the piece 8 in Figures 7 and 8. The upper surface of the part 13 is not flat but is made up of several oblique surfaces to correspond with the cross section of the key as indicated at 14 in Figure 5.

In the upper part of the box is a piece 15 which has portions 16 and 17 co-operating with the portion 13 of the piece 8 to accurately position the pieces with respect to one another. The pieces 8 and 15 constitute 95 filler blocks which serve to support, locate and guide the several moving parts within the box 5. The piece 15 has other portions 18 and 19 which conform to the outline of the housing 4. Between the part 16 and the part 18 is a passage 20 which is to accommodate the leg 2 of the shackle. A similar recess 21 separates the portion 17 from the portion 19. The passage 20 goes entirely across the housing but the passage 21 goes only part-way through the housing because it needs to accommodate only the shorter leg 3 of the shackle. There are openings 41 and 42 in the housing to accommodate the legs 2 and 3 respectively of the shackle.

The connection between the portion 18 and the portion 16 of the piece 15 is separated by a series of slots into bridge pieces 22. Each of the bridge pieces 22 has a shoulder 23 which shoulders are in line across the housing. The two end bridge members 22 are provided with slots adjacent the housing as shown at 24. These slots are made by recessing the portions of the filler block 15 which constitute the end bridge pieces 22. They are to accommodate the end of the spring 25 which goes the full length of the upper part of the passage 20 and rides upon the upper surface of the bridge pieces 22. 15 The shoulders 23 afford a stop so that the spring cannot pass further to the right than these shoulders.

These parallel slots, provided in the pieces 8 and 15, are at right angles to the passages 20 and 21. To provide these slots the up-standing portion 18 of the part 8 is cut as shown at 26. A portion of the wall of one of these slots in the middle part of the piece 15 is shown at 27.

25 The under face of the middle portion of this piece 15 is provided with several oblique surfaces as indicated at 28 to co-operate with the oblique surfaces 14 to make a key-way. These surfaces will be parallel when 30 the two operative faces of the key are parallel, so that the key is of uniform thickness; but this is not necessary. Grooves or ridges may be provided upon the key and a corresponding shape given to the key-way with- 35 out difficulty.

In the slots there slide a series of sliding locking members 29. Upon the lower edge of each of these members, which is the edge presented to the reader in Figures 7 and 8, 40 are several recesses. The central one of these, 30, is of a width to correspond with the key. This recess is rectangular so that its two ends serve to abut against the edges of the key and position the member when 45 the key is inserted, as will be later explained.

The left-hand recess 31 is arcuate. When this recess is positioned near the end of the member, as shown in Figure 9, the arc does not return to the longitudinal edge of the 50 member 29, but terminates in the end of the member. If the notch 31 is nearer the center of the member 29 the arc will return to the longitudinal edge thereof as illustrated in Figure 10. The right-hand notch 32 may 55 in the same way be completed without returning to the longitudinal edge, or may so return. Some of these members 29 are located in the housing beyond the ends of the passage 21. These members will have no 60 right-hand notch corresponding to the notch 32 as shown in Figure 9. To illustrate this, no such notch is shown in Figure 10.

The legs of the shackle are provided with grooves 33, beveled as indicated at 33'.

When the shackle is inserted fully into the 65 housing these grooves register with the grooves containing the sliding locking members 29. When these members are positioned by means of the spring 25 some portions of the lower edges of the sliding locking members will occupy the grooves 33 in the legs 70 of the shackle.

The key 34 of the lock consists of a handle and a shank 35 shown in dotted lines in Figure 8. A cross-section of this key would 75 be a zig-zag to co-operate with the key-way illustrated in Figure 5 or there may be ridges or grooves on the key to correspond to a grooved or ridged key way. The edges of the shank of the key are made undulated to 80 form cam surfaces which co-operate with the sides of the notches 30 to position each of the members 29 as illustrated in Figure 8. The end of the key abuts against the housing at the end of the key-way to definitely position these undulations with respect to the several members 29.

When the members 29 are thus positioned by the key the arcuate recesses will be in register with the surfaces of the passages 20 90 and 21 respectively and one or more of the members 29 will contact with the spring 25 at their left-hand ends as shown in Figure 8, pressing the spring 25 toward the left and leaving it out of contact with the other 95 members. When the key is withdrawn, however, the spring 25 will return all the members to the position illustrated in Figure 7. When the members 29 have been positioned to unlocked position as illustrated in Figure 100 8 the spring 10 shown in Figure 4 will eject the shackle. In this movement the spring will not travel beyond the edge of the housing, being stopped by the edge of the space 11; but the shackle can travel by its momentum until stopped as explained below.

A portion 36 of the leg 2 of the shackle is flat as shown in Figures 5 and 6, and the portion 37 beyond this flattened portion is made of equal diameter with the leg 2. 110 Some of the members 29, as illustrated in Figure 5, have the arcuate notch 31 deep enough to escape the flattened part of the leg 2 but not deep enough to permit the full-sized portion 37 of the leg to pass when the 115 spring 10 ejects the shackle 1. The outward movement of the shackle will be stopped by the contact of the head 37 with the first of the members 29 whose notch is not deep enough to permit this end to pass. 120

Between the edges 37 and the remainder of the shackle leg 2 is a groove 38 to permit rotation of the shackle relative to the housing. This enables the lock to be readily separated from whatever article is locked 125 thereby, even though the position where the lock is used may not be readily accessible. The head 37 is provided with a beveled sur-

face 39 and the end 40 of the leg 3 of the shackle is provided with a beveled surface 40.

Operation.

5 To apply the lock, the shackle 1 is passed through the parts to be secured together and then rotated into a position parallel to the plane of the base of the housing. The shackle is then thrust inward. The beveled surfaces 33' and 39 of the head 37 and grooves 33 will contact with the edges of the notches 31 in the members 29 and force the members into a position that will permit the leg 2 to pass. In the same way, the beveled portion 40 of the end of the leg 3 and surfaces 33' will contact with the notches 32 in the members 29 and force them to a position that will let this leg pass. When, however, 15 the shackle 1 arrives in its final position the grooves 33 will register with the grooves in the members 8 and 15. The spring 25 will then force the members 29 into locking position.

25 To unlock the shackle, the key 34 is thrust into the key-way until its end contacts with the housing. The undulations in the shank of the key will contact with the sides of the notches 30 in the members 29 and bring them 30 into the position illustrated in Figure 8. In this position the members 29 are all completely withdrawn from the grooves 33 and the spring 10 thereupon thrusts the shackle 1 to the position in which the head 37 abuts 35 against a member 29. The shorter leg 3 of the shackle will then be free from the housing. The shackle may be rotated about the longer leg 2 as an axis to a position in which the members which were locked together may 40 be readily freed from the shackle.

It will be observed that the only thing that needs to be different in different locks to make each lock correspond to its own key only is the position of the notches 31 and 32 45 in the several members 29. Consequently, the other parts of the lock may be made by standardized methods of manufacture such as die casting and only the cutting of these notches must be individual to each lock. Moreover, the members 29 can readily be 50 positioned in a machine by means of the notches 30 so that the accurate location of notches 31 and 32 need be only a question of correctly setting one machine.

55 I am aware that numerous details of construction may be varied through a wide range without departing from the principles of this invention, and I therefore do not pur- pose limiting the patent granted otherwise 60 than necessitated by the prior art.

I claim as my invention:

1. In a lock, a circular housing, a filler

block therein, arcuate recesses in said filler block, a spring having its ends mounted in said recesses, and a series of slidable locking 65 members actuated by said spring.

2. In a lock, a housing, a pair of filler blocks in said housing, a groove in one of said blocks, an upstanding part on the other of said blocks adapted to occupy said groove, 70 whereby the blocks are positioned relatively to each other and the housing, a keyway between said upstanding part and the floor of said groove, a series of grooves in said blocks crossing said keyway, and sliding members 75 in said last-named grooves.

3. In a lock, a housing, a filler block in said housing, comprising two depending portions, and a series of bridge pieces connecting them, a passageway between said depending portions and beneath said bridge pieces, a shackle leg sliding in said passageway, each of said bridge portions having a shoulder, said shoulders being in alignment 80 over said passageway.

4. In a lock, a shackle, having unequal legs, a housing having two passages into which the legs of the shackle enter to different lengths, a plurality of sliding locking members some movable across both of said 90 passages and the remainder movable across one only of said passages, said sliding locking members having cut away portions shaped and located so that in one position of the sliding locking members the edges of 95 the cut away portions will be flush with the surfaces of said passages, the sliding locking members which are movable across both of said passages each having two such portions and the other sliding locking members each 100 having one such portion, each of said sliding locking members having a notch whereby it may be positioned by a key, said notch being between the two cut away portions in the cases where there are two.

5. In a lock, a shackle, a housing having 105 passages into which the legs of the shackle enter, a plurality of sliding locking members movable across said passages, said sliding locking members having cut away portions 110 shaped and located so that in one position, of the sliding locking members the edges of the cut away portions will be flush with the surfaces of said passages, each of said sliding locking members having a notch whereby it 115 may be positioned by a key, said notch being between the two cut away portions.

In testimony whereof I have hereunto subscribed my name in the presence of two subscribing witnesses.

JOHN JUNKUNC.
